[57] CLAIM

The ornamental design for a combined bottle and stopper, as shown and described.

DESCRIPTION

FIG. 1 is a front elevation of a combined bottle and stopper showing my new design, the rear elevation is the same; FIG. 2 is a left side elevation thereof, the right side elevation is the same;

FIG. 3 is a top plan view of the bottle shown alone for clarity of illustration;

FIG. 4 is a bottom plan view thereof;

FIG. 5 is a front elevation of the stopper shown alone for clarity of illustration, the rear elevation is the same;

FIG. 6 is a side elevation of FIG. 5, the opposite side elevation is the same;

FIG. 7 is a top plan view of FIG. 5;

FIG. 8 is a bottom plan view of FIG. 5;

FIG. 9 is a front elevation of a second embodiment of the combined bottle and stopper, the rear elevation is the same;

FIG. 10 is a left side elevation of FIG. 9, the right side elevation is the same;

FIG. 11 is a top plan view of the bottle of FIG. 9 shown without the stopper for clarity of illustration; and,

FIG. 12 is a bottom plan view of FIG. 9.

The stopper is shown separately in FIGS. 5-8 for clarity of illustration only.
